UNITED STATES PATENT OFFICE.

SYDNEY L. BROWN, OF MAMARONECK, NEW YORK.

CAME-LEAD.

No. 896,196.

Specification of Letters Patent. Patented Aug. 18, 1908.

Application filed April 1, 1908. Serial No. 424,636.

To all whom it may concern:

Be it known that I, SYDNEY L. BROWN, a citizen of the United States, residing at Mamaroneck, in the county of Westchester 5 and State of New York, have invented certain new and useful Improvements in Came-Leads, of which the following is a specification.

My invention relates to a lead for setting 10 glass in windows commonly known as came lead. Necessarily the lead for this purpose is very pliable in order that it may be bent to conform to the contour of the sections of glass composing the window, and it is essential to the rigidity and security of the window that provision be made to resist any lateral force, such as wind pressure, which may be applied to it. With plain leads this is accomplished by stay bars set into the sash and 15 to which the leads are fastened by wire or solder. It has also been proposed to embed in the heart, during the process of manufacture of the lead, a stiffening core of tinned iron or similar material. This form in practice, however, has been found open to the serious objection that it is impossible to secure 20 a perfect joint between intersecting leads. This is due to the fact that the stiffening core is completely embedded in the heart and so concealed that the workmen cannot get at 25 the exposed end of the core which is forced between the caps of the intersected or continuous section to properly solder the joint and it frequently happens, therefore, that 30 the joints give way, resulting in a weakening of the window to such extent that it bulges and is often seriously damaged. As leaded windows in many instances can be made only at great cost, any means tending to greater 35 security during the process of making and after being placed in position is of advantage 40 in the art.

The objects of my invention are to make a lead which will enable the assemblage of the 45 window sections with the facility incident to a plain lead and by which the leads after assemblage may be reinforced or strengthened and a perfect joint effected between intersecting leads. These objects I accomplish 50 by grooving or channeling the lead in a longitudinal direction along one or both of the caps, the groove extending into the heart to any depth desired.

My invention relates primarily to the 55 grooved lead itself as it is made and sold as

an article of manufacture distinct from the strengthening rib, the latter, in practice, being laid into the groove after the window has been leaded either wholly or partially; and to the construction of the joint between intersecting leads by which I am enabled to extend the rib beyond the end of its lead so as to abut against the side of the rib of an intersected lead and to solder the same thereto to make a rigid joint.

The invention will be understood by reference to the following description taken in connection with the accompanying drawings in which

Figure 1 is a plan view of a portion of a 70 leaded window; Fig. 2 a perspective view of the strengthening rib; Fig. 3 a similar view of one embodiment of my invention; Fig. 4 a top view of two intersecting leads to illustrate the manner of joining them; Fig. 5 a 75 longitudinal section on the plane of the line 5-5 of Fig. 4; and Figs. 6 and 7 perspective views of modified forms of leads.

Similar reference numerals indicate similar parts in the several views.

In the embodiment of my invention illustrated in Figs. 3-4 and 5 the lead may be compared with a plain lead having a central longitudinal groove or channel extending through the upper cap and into the heart to any depth desired. That is, such lead comprises a continuous lower cap 1, a heart 2, and a sectional upper cap consisting of the flanges 3-3 extending laterally from the heart, the caps forming side grooves 4 to receive the glass as in a plain lead. A longitudinal groove or channel 5 extends through the upper cap and into the heart, preferably to about the depth shown in Fig. 3. It is preferred not to extend the groove 5 entirely to the lower cap 1 as that would result in weakening the lead to too great an extent. It is necessary that sufficient body should be given to the heart to prevent the collapse of the lead after it is manufactured and also in 100 its use by the workmen in leading windows. This groove runs along the median line of the cap and is open throughout its length, and in effect constitutes a pocket adapted to receive a strengthening rib 6 in the manner presently 105 to be described. In other words, the described lead instead of having a continuous upper cap and a solid heart as in a plain lead, has such cap divided longitudinally by the groove 5. The lead made by me is an inte- 110

gral structure and may be made in a press of known type provided with dies suitable for the purpose.

One of the advantages of the lead above described lies in the facility with which it may be strengthened and the joints made secure. In its use the window is leaded either partially or wholly in the same manner as a plain lead is used. Before soldering, the strengthening ribs 6, which may be of tinned iron, steel, brass or similar material, are laid into the grooves 5. Thus in Fig. 1 the rib may be laid in the binding strips 7 and 8 in continuous lengths equal to the lengths of the leads. On the panel work, however, the ribs 6 are cut in such lengths as required by the conditions met with at the joints. Thus in the interior vertical and horizontal strips the ribs 6 are longer than the corresponding leads and project beyond the ends of the lead in order to abut against the rib of the intersecting lead to which it is soldered. This manner of joining two leads will more clearly appear by reference to Fig. 4 in which the lead *a* is intersected by the leads *b* and *c*. In lead *a* the rib 6 is continuous across the intersection as in strip 9 of Fig. 1, leads *b* and *c* corresponding respectively, for the purpose of illustration, to the strips 10 and 11. In order, therefore, to solder the ribs together, the flanges 3—3, constituting the upper cap of lead *a*, and the heart of said lead, are cut through transversely to the walls of groove 5 in lead *a* and the cut sections removed to provide an opening to receive the ends of the ribs 6 to be placed in grooves 5 of leads *b* and *c*. In the former the rib 6 has been placed in position and its projecting end abutted against and soldered to the side of rib 6 of lead *a*. The lead *c* is shown as abutting against the side of lead *a*, the portion to be cut out of lead *a* to receive the rib 6 of lead *c* being indicated in dotted lines. Upon the completion of the window solder is flowed over the lead in the usual manner.

In Fig. 6 I have shown the additional groove as T-shaped in section, and the correspondingly shaped rib 13, the head of which is flush with the top of the upper cap.

Fig. 7 illustrates a further modification in which both caps are grooved. The upper cap is the same as shown in Fig. 3. The lower cap 1' is divided by a similar longitudinal groove adapted to receive a strengthening rib 6'. The heart 2' in this form consists of vertical webs joining the caps and a horizontal connecting web substantially midway between the caps.

From the foregoing description it will be seen that my invention provides means for strengthening the leads in an entirely novel

manner, and one which possesses marked utility in that the ribs are not inserted until the leads have been bent into the form required by the glass sections. By abutting the ribs of intersecting sections so that they may be soldered together a practically rigid joint may be made, this work being greatly facilitated by the fact that the groove in the lead adapted to receive the strengthening rib is open and the rib itself is at all times within access of the workmen. The window can thus be made secure at all joints between the leads and is thus able to withstand lateral pressure without danger of breaking.

What I claim and desire to secure by Letters Patent is:—

1. A came lead comprising caps forming side grooves to receive the glass, one of said caps being solid and integral with the heart, and the other of said caps having an open longitudinal groove for the purpose described. 80

2. A came lead comprising caps forming side grooves to receive the glass, one of said caps being solid and integral with the heart, and the other of said caps having an open longitudinal groove extending into the heart for the purpose described. 85

3. A came lead comprising caps forming side grooves to receive the glass, one of said caps being solid and integral with the heart, and the other of said caps having an open longitudinal groove extending into the heart, and a stiffening rib seated in said groove. 90

4. A came lead comprising caps forming side grooves to receive the glass, and an additional T-shaped open longitudinal groove for the purpose described.

5. A joint for came leads having stiffening ribs one of which ribs is continuous at the union or intersection of the leads, the rib of the intersecting section projecting beyond the abutting wall of the leads and contacting with said continuous rib through an opening in the lead of the latter. 100

6. A joint for came leads having central open longitudinal grooves and stiffening ribs in said grooves, one of the leads and rib therein being continuous at the joint or intersection of the leads and having a transverse opening in the cap leading to the central groove therein, and the rib of the intersecting lead projecting beyond the end thereof and into said transverse opening and abutting against the rib of the continuous lead. 110

In testimony whereof I have hereunto signed my name in the presence of two subscribing witnesses.
